UNITED STATES PATENT OFFICE.

FRANK DAVIS, OF PORTLAND, OREGON.

SHOW CASE.

Application filed April 5, 1924. Serial No. 704,485.

This invention relates to improvements in showcases, and more particularly to showcases for supporting and displaying packages or cartons of cakes and the like.

5 An object of the invention is to provide an improved showcase which will be so constructed as to support a plurality of cartons in such a manner that the lowering of a shelf will automatically raise a lid so that 10 access may be had to the interior of the carton.

Another object of the invention is to provide an improved showcase which will be provided with a plurality of carton-receiving cases, which will be fixedly secured in suitable racks in such a manner as to display goods or edibles within the cartons positioned within said cases.

20 A further object of the invention is to provide a showcase construction which will support and display a plurality of cartons, and other contents, and furthermore the provision of a pivoting shelf which will be connected to cover or lid for each of said cartons so that when the shelf is lowered, the lid will be raised and the lid being heavier will close automatically when no weight is 25 on the shelf.

A still further object of the invention is 30 to provide an improved showcase of the character described which will be highly efficient in use and quite inexpensive to manufacture.

Other objects will appear as the description proceeds.

In the accompanying drawings, which form a part of my application—

Figure 1 is a side elevation of my improved showcase;

40 Figure 2 is a front elevation of the showcase;

Figure 3 is a vertical sectional view of the showcase;

45 Figure 4 is a perspective view of one of the carton supporting cases;

Figure 5 is a perspective view of a portion of one of the carton supporting cases showing in detail, the retaining means for holding the cartons in position;

50 Figure 6 is a side elevation particularly in section of one of the carton containing cases, showing the cartons in dotted lines;

Figure 7 is a perspective view of a case-receiving or supporting rack;

55 Figure 8 is a detailed view of the means

for locking a case in the case-receiving rack, and

Figure 9 is a perspective view of one of the shelf supporting rails or yokes.

Like characters of reference are used 60 throughout the following specification and the accompanying drawings designate corresponding parts.

The showcase comprises a form construction consisting of four corner posts 1, which 65 are connected together at their opposite ends by means of the spaced end strips 2. A shelf 3 extends transversely from side to side of the case and serves to more rigidly brace the same.

70 A plurality of case-supporting racks are positioned between the opposite sides of the showcase, and are formed of two triangular shaped ends 4 which are connected together on two of their adjacent sides by means of 75 the strips 5. Slots 6 are formed in the upper and lower portions of the triangular shaped ends 4 and are adapted to receive supporting bolts 7.

The racks comprising the triangular 80 shaped portions 4 and connecting the strips 5 are adapted to receive and support a plurality of carton receiving cases 8. These cases 8 are formed with backs 9, bottoms 10, front shelves 11, which are hinged to the 85 bottoms 10, sides 12 and hinged transparent covers 13. A downwardly extending binding strip or band 14 is hinged at 15 at the opposite sides of the case, and is cut on slantingly at its rear ends, and is adapted 90 to be raised as best illustrated in Figure 6 of the drawings when it is desired to place a carton within the case, but if they are of half the usual size, a filler 16 may be inserted first within the case to hold the cartons 17 at the proper distance from the bottom of the case.

95 Each of the cases has positioned on its back, a wedge-receiving socket 18 which is adapted to extend between adjoining strips 5 on the 100 case-receiving racks, and when said cases are in position, they are held securely by inserting the wedge 19 through the socket 18. An element 20 of a strap hinge is positioned at one or both sides of each case and is attached to each shelf 11. The second element 21 of the hinge is pivoted to the hinged cover 13 and has a pivoted connection at a point adjacent the outer or rear end of the element 20 as at 22. A bell or gong 23 is pivoted at 110

- 24 on a side of each case and is engaged by the free end of the element 20 whenever the front shelf or cover is moved from its normal position.
- 5 The shelves 11, as before mentioned are hingedly connected to the cases, and are provided with spring tensioning means 40, which serves to assist in closing the lid and holding it closed.
- 10 A beveled finger 41 is provided at the outer end of each of the shelves 11, and is adapted to seat within a slot or notch 42 in the rim of the cover 13, when the cover and shelf are both closed.
- 15 The mode of operation of my improved showcase is as follows: Assuming that a carton is in position within each case, the goods within said cartons may readily be seen through the transparent tops of the cases.
- 20 When a customer has decided upon the goods or edibles he intends to purchase, the salesman will grasp the handle 25 on the shelf 11, and pull down same, which action will cause the knife hinge to open, first sounding the gong 23 and then lifting the cover 13.
- 25 The shelf 11 will then extend in a substantially horizontal position and may support the bag or container into which the goods will be placed. A shelf supporting rail or yoke 26 is pivoted at 27 and extends the full width across the showcase and is adapted to contact with pins 28 to hold the same in position. The pins 28 may of course be inserted in any desired adjusted position. The shelves 11, when in lowered or horizontal position will be supported upon the rail or yoke 26, thereby taking any undue strain from the cases. After the desired amount of the goods or edibles have been removed from the cartons, the covers may be lowered to their normal position, which movement will simultaneously close the shelves due to gravity, and the covers being heavier than the shelves.
- 30 The gong 23 will serve to notify the salesman in the event that an unauthorized person opens the case.
- 35 Many minor changes in detail of description may be resorted to without departure from the spirit of the invention.
- 40 After thus describing my invention what I claim as new, and desire to secure by Letters Patent of the United States, is:
- 45 In a show case, having a supporting stand, a plurality of case supporting racks adjustably supported thereby, a plurality of carton receiving cases detachably secured in said racks, pivoted interconnected tops and shelves attached to each of said cases, a pivoted band attached to the top of each of said cases and positioned below said main tops or covers, and means for supporting said shelf when in lowered position to limit the movements thereof.
- 50 In testimony whereof I affix my signature.
- 55 FRANK DAVIS.
